PUMPING APPARATUS FOR OIL WELLS

Warren M. Mansfield, Glendale, Calif., assignor to
Emsco Derrick & Equipment Company, Los
Angeles, Calif., a corporation of California

Application January 23, 1939, Serial No. 252,430

7 Claims. (Cl. 308—21)

My invention relates in general to pumping apparatus for use in pumping oil wells, and more particularly relates to a walking beam bearing and support therefor which is useful in supporting the walking beam on the Samson post.

It is common practice at the present time to support a walking beam on a bearing mounted at the upper end of a Samson post. One end of the walking beam rests above the well and has the polish rod of a string of sucker rods connected to it. It is highly desirable that the end of the walking beam be rather accurately adjusted with respect to the vertical axis of the well in order that accurate alignment may be had. It is further highly desirable that a means be provided whereby the walking beam may be readily moved into a retracted position in order that free access may be had to the space above the oil well during the removal or installation of pump parts or sucker rods.

It is an object of my invention to provide a walking beam bearing and support assembly whereby the end of the walking beam may be adjusted into an accurate aligned position over the well.

It is an object of my invention to provide a simple arrangement whereby this adjustment may be accomplished.

It is a still further object of my invention to provide a walking beam bearing and support assembly in which the walking beam bearing having the walking beam secured thereto is quickly demountable from the walking beam bearing support on the Samson post in order that the walking beam may be easily retracted into a position which gives full access to the space above the well.

It is a still further object of my invention to provide a walking beam bearing and support assembly in which the walking beam bearing is readily demountable and in which the parts cooperate to provide coengaging walls which restrain the walking beam bearing from bodily movement in a direction longitudinal of the walking beam which is secured to the bearing.

It is a still further object of my invention to provide a walking beam bearing and support assembly in which the bearing and support cooperate to provide a V-shaped recess and a V-shaped projection having coengaging walls which extend at angles to vertical and in which these walls are moved into coengagement by the action of gravity, and when the parts are secured together by a simple securing means, such as a bolt, adequately restrain the bearing from

bodily movement in a direction longitudinal of the walking beam.

It is a further object of the invention to provide a walking beam bearing of simple and durable form having an adjustable plate which is connected rigidly to the walking beam and has cooperating adjustment means whereby it may be adjusted relative to the bearing and to the Samson post on which the bearing is mounted, whereby adjustment of the position of the walking beam may be readily accomplished.

A further object of the invention is to provide a walking beam bearing having upper and lower cooperating bearing parts which are connected together within a substantially closed bearing chamber so formed that the volume of the space contained within the bearing chamber will not change due to the relative swinging movement of the parts, and so that there will consequently be no alternate intake and exhaust of air into and from the bearing chamber to carry dust to the working parts of the bearing.

It is a further object of the invention to provide a unitary walking beam bearing of such form that it may be readily and amply lubricated, and in which the cooperating bearing faces are so formed that the bearing unit may be operated for long periods of time and without attention.

Further objects and advantages of the invention will appear in the following part of the specification.

Referring to the drawings which are for illustrative purposes only:

Fig. 1 is a side elevation of a preferred form of my invention.

Fig. 2 is a view looking toward the rear end of the device shown in Fig. 1.

Fig. 3 is an enlarged fragmentary view of the portion of Fig. 1 included within the dotted circle 3 thereof.

Fig. 4 is a face view of one of the counterbalance plates.

Fig. 5 is an enlarged fragmentary, partly sectioned view of the walking beam bearing taken from the position indicated by the line 5—5 of Fig. 1.

Fig. 6 is an enlarged elevational view of the walking beam bearing cross-sectioned substantially as indicated by the line 6—6 of Fig. 5.

Fig. 7 is an enlarged perspective view of the cylindrical bearing body and the saddle forming part of the upper bearing part of the walking beam bearing.

Fig. 8 is a partly sectioned perspective view of the lower bearing part.

Fig. 9 is a perspective view of one of the bearing hold-down members.

Fig. 10 is an enlarged perspective view of a guard plate forming a part of the walking beam bearing.

As shown in Figs. 1 and 2 of the drawings, my pumping unit comprises a base 10 which is preferably fabricated from sheet steel and standard structural members. Rigidly secured to, and extending upward from the front end of the base 10 there is a Samson post 11 carrying a walking beam bearing 12 which supports a walking beam 13 having means 14, commonly referred to as a horse head, and cable means 15 for attachment to the upper end of a polished rod 16 which projects from a well head 17 and forms the upper end of a string of sucker rods for operation of a pump located in the well. On the base 10 rearwardly of the Samson post 11 there is a power unit 18 having a pair of cranks 19 which are connected through rod or link members 20 with a cross arm 21 which is connected in laterally extended position to the rear portion 22 of the walking beam 13 by suspension means 23 situated forwardly of the rear end 24 of the walking beam 13.

I provide a simple form of counterbalance means 25. This counterbalance means comprises a plurality of plates 26 resting in face to face relation and being adjustable along the walking beam 13 relative to the point of fulcrum of the walking beam represented by the walking beam bearing 12. The walking beam 13 consists of a standard steel structural member having a horizontal flange 25a along the lower portion thereof. Preferably this walking beam 13 consists of an I-beam, but in the preferred practice of the invention, only the lower flange 25a is employed for the support of the counterbalance 25. As shown in Fig. 4, each counterbalance plate 26 has an opening 27 therein to permit it to be slid onto the rear portion of the walking beam 13 into operating position, as shown in Figs. 1 and 2. Preferably each opening 27 comprises a vertical slot 28, leading down from the upper edge of the plate 26 to receive the flange of the I-beam, and an enlargement 29 at the lower end of the slot 28 to receive the flange 25a of the I-beam. The plates 26 hang from the flange 25a and the group of plates 26 forming the counterbalance 25 is held in position by locking members 30 which are so formed that they may be readily adjusted along the flange in accordance with the position selected for the counterbalance means 25 on the walking beam 13. Each locking device 30, as shown in Fig. 3, comprises a plate 31 having an inverted T-shaped opening 32 to receive the flange 25a and the lower portion of the web 33 of the I-beam. Each plate 31 is provided with a screw 34 at the lower end thereof, adapted to bear against one side of the counterbalance means 25, and each plate 31 has a relatively sharp shoulder 36, formed by a dog 37 comprising a square bar of hard alloy secured to the front face of the plate by means of a weld 35. When outward reaction is applied to the lower end of the plate 31 by the application of the screw 34 to the counterbalance means 25 the shoulder 36 is caused to dig into or frictionally engage the lower face of the flange 25a so as to restrain the locking device against movement away from the face of the counterbalance means. The counterbalance may be adjusted forwardly or rearwardly on the walking beam 13 and the weight thereof

may be changed by increasing or decreasing the number of plates 26.

The Samson post is formed from a plurality of structural angles 38 spaced relatively far apart at their lower ends where they are secured to the base 10 by means of anchor plates 39. The upper ends of the angles or legs 38 are brought relatively close together and are welded to a bearing support or support member 41 comprising a short section of a structural angle placed so that the legs 42 thereof, Fig. 6, slope upward and outward at an angle of substantially 45° to horizontal, thereby forming a depression or recess 43 which extends laterally with respect to the walking beam 13.

As shown in Figs. 5 and 6, the walking beam bearing 12 is fitted in the opening 43 provided by the support 41 and is secured therein by bolt means disclosed as cap screws 44. This walking beam bearing has a lower bowl section 45, as shown in Figs. 5, 6, and 8, which includes a semi-cylindrical wall 46 preferably cast from steel and having formed thereon two downwardly projecting walls or webs 47 disposed near the ends of the wall 45 and an intermediate downwardly projecting wall or web 47a placed substantially centrally between the walls or webs 47, there being a V-shaped bar 48 integrally formed with and connecting the lower portions of the walls 47 and 47a together. The walls 47 and 47a have edge faces 49 disposed substantially perpendicularly to each other, and tangential to the axis of the cylindrical wall 46, in position to fit snugly against the inner faces of the legs 42 when the cap screws 44 are screwed up tight in the threaded openings 50 provided therefor in the bar 48. The formations 45, 47, 47a, 48, and 49 constitute a base member of the bearing and this base member provides a projection which has walls arranged at an angle to vertical which coengage the walls of the support member, and since these coengaging walls are extended at angles, it will be seen that they are held in engagement by gravity and when one part is placed in the other they are self-aligning so that the securing bolt 44 may be readily installed. It will further be seen that when the securing bolt has been installed the coengaging faces cooperate to prevent the bearing from moving bodily in a direction longitudinally of the walking beam 13.

The cylindrical wall 46 has diagonally opposed lugs 51 provided with threaded openings 52, and diagonally opposed lugs 53 equipped with threaded openings 52. The lugs 51 and 53 support stop members 54 in the form of ears which project from the lugs 51 and 53 toward a central plane perpendicular to the axis of the wall 46. The wall 46 supports a semicylindrical wall 55 of a suitable bearing metal which defines a semicylindrical socket 56 the ends of which are closed by semicylindrical plates 57.

As shown in Figs. 5, 6, and 7, the bearing 12 has an upper portion 58 comprising a plug 59 to fit into the socket 56 and a plate or saddle 60, fixed on the plug 59, on which the walking beam may be supported. The plug 59 comprises a cylinder, preferably of hollow character in that it has an axial opening 61 therethrough. The saddle 60 comprises a horizontal wall 62, the width of which is less than the length of the cylinder 59 so that the end portions 63 of the cylinder 59 will project beyond the vertical planes defined by the edges 64 of the wall 62. The wall 62 has webs 65 projecting downwardly therefrom for engagement with the upper face of the cylinder 59. The

arc of engagement of the web 65 with the cylinder 59 is substantially 90°.

The saddle 60 has bolt openings 66 which are elongated in a direction transverse to the axis of the plug 59, and has diagonally disposed dogs 67 for engaging the stop members 54 when the saddle 60 is swung downward in either direction from the horizontal position in which it is shown in Fig. 6.

The cylinder 59 is of such diameter that the lower half thereof will make bearing fit with the semicylindrical socket 56. When the cylinder 59 is placed in the bowl portion 45, thrust rings 68 are placed at the ends thereof, and the exposed end portions 63 of the cylinder 59 are covered by hold-down members 69 of the form disclosed in Fig. 9. These hold-down members 69 each include a semicylindrical wall 70 with an outwardly projecting flange 71 at the inner end thereof and a semicylindrical end wall 72 to cooperate with an end wall 57 of the lower bearing portion. The members 69 are provided with projecting lugs 73 having openings 74 therein through which screws 75 may be passed into the threaded openings 52 of the lugs 51 and 53 of the bearing bowl 45. When the members 69 are secured in place, as shown in Fig. 5, narrow spaces exist between the inner ends of the hold-down members and the edges 64 of the saddle 60, and cover plates 76 are secured in depending relation to the edges 64. Each cover plate 76 comprises a rectangular wall 77 with a semicircular opening 78 in the lower portion thereof, a narrow semicylindrical wall 79 around this opening and a lip or flange 80 extending inwardly from the edge of the wall 79. The plate 77 has screw openings 81 through which screws 82 are passed into threaded openings 83 in the edges of the wall 62 of the saddle member when the cover members 76 are placed, as shown in Figs. 5 and 6, with the plate 77 thereof engaging the edges 64 and with the cylindrical walls 79 and flanges 80 lying over the flanges 71 of the hold down members 69.

Arcuate plates or walls 83, generated on the axis of the cylinder 59, are secured to the lower face of the saddle 60 by means of screws 84 passed through flanges 85 formed at the upper edges of the walls 83. These arcuate walls are placed so as to project downward on the opposite sides of the semicylindrical wall 46 of the bearing bowl 45. The arcuate walls 83 are of such length that the ends 86 thereof engage the inner faces of the plate 77, and outward movement of the lower portions of the plates 83 is limited by lugs 87 which project from the inner faces of the plate 77. The upper portions of the arcuate plates 83 and the part of the wall 62 between the upper ends of the plates 83 cooperate with the flanges 71 of the hold-down members 69 and the plate 77 in forming a bearing chamber 89 above the exposed portions of the semicylindrical walls 46 and 55. Sealing means between the arcuate plates 83 and the upper edges of the wall 46 are provided in the form of wiper strips 90, held by cleats 91 in position to project from the upper edges of the wall 46 into engagement with the inner faces of the arcuate plates 83. This bearing chamber 89 is symmetrical on opposite sides of the upper portion of the bearing pin or cylinder 59 when the saddle 60 is in horizontal position, and as the saddle 60 rocks so that the arcuate plates 83 slide up and down relative to the wiper strips 90, air will flow across the top of the cylinder 59 from one side to the other of the bearing chamber 89, the volume of which bearing

chamber remains constant so that rocking of the upper bearing part in the bearing bowl will not cause a breathing of air in and out of the bearing chamber 89.

5 The saddle 60 forms a part of an adjustable means for securing the walking beam 13 to the walking beam bearing 12. On the wall 62 a plate 93 rests, this plate being secured to the flange 25a of the walking beam, and being securable to the wall 62 by means of bolts 94 which pass through the slots 66 in the wall 62. The plate 93 is longer than the wall 62 and has downwardly projecting bodies 95 with threaded openings 96 to carry adjusting screws 97 in such position that the ends thereof may be applied to the ends of the wall 62. By suitable operation of the screws 97, the plate 93 may be shifted forward or rearward relative to the walking beam bearing to bring the horse head 14 into a desired position above the polish rod 16 whereupon locking nuts 98 on the screws 97 may be tightened, and the bolts 94 may be tightened so that the plate 93 will be locked in the selected position of operation.

As a means for providing ample and constant lubrication for the bearing faces of the cylindrical plug bearing member 59 and of the bearing socket 56, I connect an oil spout 99 with the interior of the bearing bowl 45 and the axial opening 61 of the cylinder 59 through a nipple 100 which threads through one end wall 57 of the bearing bowl 45. When the upper closure or cap 101 of the oil spout 99 is removed, oil may be poured through the oil spout 99 so as to substantially half fill the interior space of the cylinder 59. Portions of this oil flow through radial openings 102 in the wall of the cylinder 59 to the bearing faces to continuously lubricate the same for relative rocking movement of the cylinder in the bearing socket. When it is desired to drain the oil from the interior of the cylinder 59 the lower plug 103 of the oil spout 99 may be removed.

When it is desired to work on the well, for example to pull the oil tube, the walking beam may be shifted back so that the horse head 14 will assume the position indicated by dotted lines 14' in Fig. 1. For use at this time, the walking beam 13 is provided with a projection 100 on the lower face thereof adjacent the horse head 14, this member 100 being shown as a plate bent to V-shaped form to correspond substantially to the bearing support 41 at the upper end of the Samson post 11. When it is desired to shift the walking beam to retracted position the bolts 44 are removed so that the bearing 12 may be lifted bodily from the support 41 by raising the walking beam, the projection 100 being then brought to rest in the support 41 and the screws 44 then being passed through the lower part of the bearing support 41 into engagement with the projection 100 to firmly secure the same in place.

I claim as my invention:

1. In a walking beam bearing and support therefor, the combination of: a support comprising an angle with means for holding the same in a position with the legs thereof diverging upwardly so as to form an upwardly faced channel; a bearing bowl having angularly disposed walls on the lower portion thereof to fit into the upwardly faced channel formed by said legs of said angle, there being bolt means to secure said bearing bowl to said angle, said bearing bowl having an upwardly faced semicylindrical wall forming a semicylindrical bearing socket closed by end walls; a bearing body comprising a hollow cylinder, the lower portion of which fits into said

bearing socket; hold-down members supported by the end portions of said bearing bowl in position to extend over the ends of said cylinder; and a saddle member connected to the upper portion of said cylinder between said hold-down members, there being means for connecting said saddle member to said walking beam.

2. In a walking beam bearing and support therefor, the combination of: a support comprising an angle with means for holding the same in a position with the legs thereof diverging upwardly so as to form an upwardly faced recess; a bearing bowl having angularly disposed walls on the lower portion thereof to fit into the upwardly faced recess formed by said legs of said angle, there being bolt means to secure said bearing bowl to said angle, said bearing bowl having an upwardly faced semicylindrical wall forming a semicylindrical bearing socket closed by end walls; a bearing body comprising a hollow cylinder, the lower portion of which fits into said bearing socket; hold-down members supported by the end portions of said bearing bowl in position to extend over the ends of said cylinder; a saddle member connected to the upper portion of said cylinder between said hold-down members; a plate adjustably connected to the saddle member; means for connecting said plate to the walking beam; and means for delivering oil into said hollow cylinder.

3. In a walking beam bearing and support assembly for use between a Samson post and a walking beam, the combination of: a bearing comprising a saddle whereby the walking beam may be secured on said bearing for reciprocatory movement and a base member pivotally connected to said saddle and forming the lower part of said bearing; a support member adapted to cooperate with said base for supporting said bearing, one of said members providing a recess and the other of said members providing a projection which fits into said recess, said members providing angularly disposed coengaging walls which cooperate to restrain said bearing from moving in a direction longitudinally of the walking beam; and means for removably securing said bearing to said support member.

4. In a walking beam bearing and support assembly for use between a Samson post and a walking beam, the combination of: a bearing comprising a saddle whereby the walking beam may be secured on said bearing for reciprocatory movement and a base member pivotally connected to said saddle and forming the lower part of said bearing; a support member adapted to cooperate with said base for supporting said bearing, one of said members providing a substantially V-shaped recess and the other of said members providing a substantially V-shaped projection which fits into said recess, said members providing angularly disposed coengaging walls which

cooperate to restrain said bearing from moving in a direction longitudinally of the walking beam; and means for removably securing said bearing to said support member.

5. In a walking beam bearing and support assembly for use between a Samson post and a walking beam, the combination of: a bearing comprising a saddle whereby the walking beam may be secured on said bearing for reciprocatory movement and a base member pivotally connected to said saddle and forming the lower part of said bearing; a support member adapted to cooperate with said base for supporting said bearing, one of said members providing a recess and the other of said members providing a projection which fits into said recess, said members providing coengaging walls so positioned and arranged to cooperate to restrain said bearing from moving in a direction longitudinally of the walking beam; and bolt means extending through the bottom of said recess and projection for securing said bearing to said support member.

6. In a walking beam bearing and support therefor, for use in reciprocably supporting a walking beam, the combination of: a bearing support including an angle plate positioned with the legs thereof diverging upwardly to form a V-shaped recess; a bearing unit having a base shaped to be received in said recess and having walls engaging said legs and an upper part pivotally connected to said base and having means securing it to said walking beam, said bearing being readily separable from said support; and means for removably securing said base in said recess.

7. In a walking beam bearing and support assembly for use between a Samson post and a walking beam, the combination of: a bearing comprising a saddle whereby the walking beam may be secured on said bearing for reciprocatory movement and a base member pivotally connected to said saddle and forming the lower part of said bearing; a support member adapted to cooperate with said base member for supporting said bearing, one of said members providing a recess and the other of said members providing a projection which fits into said recess so that by relative vertical movement of said base member said projection may be moved freely into and out of engagement with said recess, said members providing coengaging walls so positioned and arranged to cooperate to restrain said bearing from moving in a direction longitudinally of the walking beam; and releasable means for removably securing said base member to said support member, said securing means being formed so as to impart opposed substantially vertical force to said members so as to hold them in coengagement and permitting disengagement of said members when released.

WARREN M. MANSFIELD.
